UNITED STATES PATENT OFFICE.

FRANK J. PRAME, OF SHILOH, OHIO.

BLAST-REGULATOR FOR GRAIN AND SEED CLEANERS.

No. 823,637.

Specification of Letters Patent.

Patented June 19, 1906.

Application filed July 14, 1905. Serial No. 289,576.

To all whom it may concern:

Be it known that I, FRANK J. PRAME, a citizen of the United States, and a resident of Shiloh, county of Richland, and State of Ohio, have invented a new and useful Improvement in Blast-Regulators for Grain and Seed Cleaners, of which the following is a specification, the principle of the invention being herein explained and the best mode in 5 which I have contemplated applying that principle, so as to distinguish it from other inventions.

My invention relates to machines for cleaning grain and seed, and particularly to devices for regulating the air-blast in such machines. Some means for securing such regulation are quite essential if the same machine is to be used for cleaning different kinds of seed, for only a very light blast is needed in 10 handling fine light stock, whereas a strong blast is required for heavy stock.

The object of my invention then is to supply means for effecting such regulation that shall be capable of ready and exact adjustment to meet varying requirements.

Said invention consists of means hereinafter fully described, and particularly set forth in the claims.

The annexed drawings and the following 30 description set forth in detail certain means embodying the invention, such disclosed means constituting but one of the various mechanical forms in which the principle of the invention may be used.

35 In said annexed drawings, Figure 1 represents a vertical longitudinal cross-section of a grain-cleaner with my improved blast-regulator in place. Fig. 2 shows the essential parts of the regulator in perspective. Fig. 3 shows the same partly in cross-section and partly in elevation, and Fig. 4 shows in enlarged transverse cross-section the drum and a portion of the air-shaft contiguous thereto whereby the relative disposition of these 45 parts more clearly appears than in Fig. 1.

The grain-cleaner in connection with which my improved blast-regulator is shown in Fig. 1 is intended to be merely typical of the general class of machines to which such regulator

50 is designed to be applied. In the cleaner there shown, A is the hopper from which grain is admitted to the interior of the machine by opening a slide A'. Upon being admitted the grain first falls upon a screen B.

55 Then after passing through such screen it is borne down the inclined way C, from the

lower end of which it is discharged into a vertical air-shaft E. A continuous blast of air is forced upward through this shaft by means of a fan D, rotating in a drum D', the air being admitted to the drum at either end in the usual manner. When the air-current, passing thus through shaft E, is of the right force, upon the grain being admitted, as just described, to such shaft the perfect kernels are separated from the chaff, fine dust, and imperfect kernels, these latter being carried along with the current and discharged through hood F, while the slightly-heavier perfect kernels continue downward and are fed through spout E' into a box H.

The description of the cleaner as thus far given would apply to any modern form of the machine. The element that constitutes my invention and adds greatly to the usefulness of the cleaner is a device by means of which I regulate the force of the blast or current passing upwardly through air-shaft E. The necessity for such regulation is quite evident from the principle of operation of the cleaner just given, for unless the current of air is of the proper force either good kernels will be borne along with the chaff and dust or else the latter will be only partially separated out.

Attempts have heretofore been made to effect such regulation of the air-blast by variably closing, by means of slide-doors, the ends of the air-drum or by varying the speed of the fan. The first of these methods has the objection that when the supply of air to the fan is reduced by partly closing the doors the blast is apt to fluctuate and to be stronger at the center of the air-shaft than at the sides, while the second method involves the use of cone-pulleys or similar means which occupy valuable space and are not always easy or convenient to manipulate. The means by which I effect such regulation of the blast comprise, as shown in the figures of the accompanying drawings, a novel arrangement 85 of the lower lip d of the air-drum D' where it opens into the throat of the air-shaft E and an adjustable valve R in such throat of the air-shaft.

Lip d of the air-drum, as clearly shown in Figs. 1 and 2, is flared outwardly or depressed from the arc of the circle that it would lie in were it to conform exactly in curvature with other portions of the drum. By this construction it is readily apparent that the blast 90 of air discharged from the drum is properly deflected to pass up the air-shaft and to fill 95 100 105 110

from the first the entire cross-sectional area of the same. Such outwardly-flared lip is particularly advantageous when the valve, later to be described, is closed down, so as to 5 leave only a very narrow slit for the air to pass through, as would be the case when cleaning light seed. In such case were it not for the lip the blast of air would be discharged in a substantially radial direction and impacting 10 against the opposite wall of the throat would be deflected downwardly, as well as upwardly, with consequently imperfect winnowing effect, whereas the lip gives an approximately tangential direction to 15 such escaping current of air with the result above noted.

The valve R preferably consists of a rectangular piece of sheet-iron or other suitable material bent in one direction to conform 20 with the curvature of the air-drum, so that it is, in effect, a section of a cylindrical surface. It extends entirely across the throat of the air-shaft and is of a width sufficient when lowered to completely close such throat. 25 When raised, the valve is designed to slide within the air-drum, the radius of this portion of the drum being increased in order to provide room for the valve between the fan and the inner surface of the drum. Projecting 30 tongues r , one at each end of the valve and designed to fit in curved grooves r' on the inner surface of the siding or frame of the cleaner, serve to guide the valve as it is thus raised and lowered. Such raising and lowering is effected by means of racks r^2 , one at 35 each end of the valve, and pinions r^3 , meshing therewith. The pinions r^3 are both mounted upon a single shaft r^4 , so that by turning this shaft it is evident that the valve can be 40 quickly positioned, as desired. A hand-wheel r^5 , attached to a projecting end of shaft r^4 , facilitates such turning, while a set-screw r^6 in one of the bearings r^7 , in which the shaft turns, serves to secure it against further turning when once the valve is properly adjusted.

Having thus described the construction of my regulator, the manner of its operation is easily indicated. The fan D is designed to be

operated at a uniform rate of speed, and the 50 ends of the air-drum are not obstructed by half-closed doors or the like. In this manner and by means of the peculiarly-shaped lip d of the air-drum a steady current of air of uniform force throughout is thus maintained in 55 air-shaft E. To accommodate this current to seeds or grain of different qualities, it is merely necessary to more or less completely close valve R by the mechanism provided for that purpose. It is clear, however, that even 60 when very nearly closed, as would be necessary in cleaning very light seed, the air is still admitted with equal force along the entire width of the throat of air-shaft E. Accordingly the separating effect of the current in 65 such shaft is uniform and constant.

Having thus described my invention in detail, that which I particularly point out and distinctly claim is—

1. In a grain and seed cleaner, the combination of a substantially vertical air-shaft, an air-drum laterally contiguous thereto and opening therein, the lower lip of said drum where it opens into said air-shaft being flared outwardly, a valve of cylindrical shape to 75 conform to the shape of said drum fitted within the upper part of the same and movable toward and from said lower lip, and a rack and pinion for positioning said valve.

2. In a grain and seed cleaner, the combination of an air-drum, a fan therein, a substantially vertical air-shaft open at both ends and connected with said air-drum, the lower lip of such air-drum where it opens into said air-shaft being flared outwardly, a valve of cylindrical shape to conform to the shape of said drum slidably mounted in the opening between said drum and air-shaft, a rack transversely mounted on said valve, a shaft bearing a pinion adapted to mesh therewith and 85 provided with a handle, and a set-screw adapted to hold said shaft against turning.

Signed by me this 10th day of July, 1905.

FRANK J. PRAME.
